UNITED STATES PATENT OFFICE.

CHARLES H. MORGAN, OF WORCESTER, MASSACHUSETTS.

REELING MECHANISM.

SPECIFICATION forming part of Letters Patent No. 334,453, dated January 19, 1886.

Application filed July 7, 1885. Serial No. 170,863. (No model.)

To all whom it may concern:

Be it known that I, CHARLES H. MORGAN, a resident of Worcester, in the county of Worcester and State of Massachusetts, have invented a new and useful Improvement in Reeling Mechanism for Wire-Rod-Rolling Mills, which improvement is fully set forth in the following specification.

The object of my invention is to provide a means whereby the reel or reels of a wire-rod-reeling machine may be run at a low rate of speed in coiling said rods thereon, thereby greatly reducing the wear and tear of machinery for operating said reels, and consequently causing a large saving in the cost of production over fast running reels.

It relates to rolling-mills having a primary train of reducing-rolls and one or more supplementary trains used in combination with said primary train, such as shown and described in a previous application of a similar nature.

It consists in the combination of two or more reels arranged in proper receptacles having adjustable covers, and provided with means for maintaining the heat of the rods deposited in said reels, with means for operating the reels, for conducting the rods from the last set of primary rolls to said reels, for distributing them in coils or loops therein around its central spindle or cone, and for guiding the rods when drawn forward from said reels to the supplementary trains, as hereinafter more fully explained.

It also consists in the combination of the reels and operating mechanism with a distributing device for depositing the rods as fast as fed forward, in small loops or coils overlapping each other, around the central cones of said reels, as will also be hereinafter more fully described.

To enable those skilled in the art to which my invention appertains to make and use the same, I will proceed to describe it more in detail.

In the accompanying drawings, Figure 1 is a plan view of an apparatus constructed in accordance with the invention, and Fig. 2 a vertical section of the same.

50 C represents a brick inclosure, which in this instance is made square, as shown by dotted lines a in Fig. 1. Said inclosure is made of

the proper size and shape to receive the reel-driving mechanism, as shown in Fig. 2.

The reels D, of which there are four in this instance, as shown in Fig. 1, are arranged in proper inclosures or receptacles, D', contained within or forming a part of the large circular inclosure or furnace E, which is provided with a suitable number of inlet-pipes, F, through which to supply the furnace with gas, and with an outlet-flue, G, for carrying off the products of combustion. The furnace E and its reel-inclosures D' are, in practice, made of fire-brick. Combustion may be maintained in said furnace or not while the apparatus is in use, according to different requirements—as, for instance, if the rods are to be at once further reduced in size by passing through supplementary trains, it is necessary to maintain or increase the temperature of the same during the interval between the reducing operations. The combustion is therefore kept up in said furnace; but if the rods are to be unwound from said reels, coiled upon other reels, and stored for future treatment, it is of course unnecessary to maintain said combustion. Each reel D is provided with a central cone, b, and is mounted on the upper end of a sleeve, c, to the lower end of which is fastened the large spur-gear, H, and the upper half, d, of a friction-clutch, I. Said parts are driven to turn the reels by connection with the main driving bevel-gear J through the bevel-gear K, shaft L, spur-gear M, spur-gears N, shafts O, and the cones e, fastened to the upper ends of said shafts, which are forced up in clutch with their respective parts d, and a sufficient distance farther to raise said parts d off of the stationary bearing parts f by means of the hydraulic pistons P, which are provided at their upper ends with suitable steps to receive the lower ends of the shafts O. Said shafts are fitted to turn at their upper ends in bearings O', fastened to the cross-beam O''. The shaft L, to which the bevel-gear K and spur-gear M are secured, is fitted to turn at its upper end in a bearing, L', and at its lower end in a step, L''. The shafts O (which extend up into and are fitted to turn in the sleeves c) and their cones e are turned continuously; but the reels are turned only when said shafts and cones are forced up, as hereinbefore described. When the reels and other parts connected

thereto are lowered with the cones *e* out of contact with the part *d*, the inner beveled sides, *d'*, of said cones rest upon the beveled sides *f'* of the stationary bearing parts *f*, and 5 are thereby held in a stationary position. Therefore, as will be seen, the clutches I serve the double purpose of connecting the driving power to turn the reels and of quickly stopping said reels when the driving power is re-10 moved.

Previous to my invention it has been customary to coil the rods around the central cone, *b*, of a reel similar to the ones shown in the drawings, (with the exception of being 15 smaller in diameter,) by either feeding the rods in at one point and rotating the reel, or by distributing said rods upon a stationary reel as fast as delivered around said central cone by means of a swinging distributing device. 20 vice. Both of said methods, and especially the former, are objectionable, for various well-known reasons, and have, consequently, never been applied to general use. To obviate such objections, I have adopted the following method and means for reeling wire rods. I make the reels *D* about double their usual diameter, and, instead of forming one coil around the central cones, I distribute the rods as fast as delivered in single loops *g* (see Fig. 1) 25 around the inside of the reels, outside of said central cones, and while said reels are slowly revolving by means of suitable rotating or swinging distributing devices or distributors operated by connection with the driving mechanism of said reels.

In the drawings I have represented at the right-hand side of the figures rotating distributing devices *Q* *Q'*, and on the left-hand side the swinging distributing devices *Q* *Q'*. 30 The rotating distributors are fitted to turn in suitable bearings in the inner ends of the stationary frames *R*. They are each provided with a conducting-pipe, *h*, having a flaring or trumpet-shaped opening at the top, with a 35 holding-flange, *i*, and with a small spur gear or pinion, *j*, at the bottom, by means of which said devices are turned by power imparted from the large spur-gears *H* on shafts *O*, through the spur-gears *S*, shafts *T*, spur-gears 40 *U*, and spur-gears *V*, the latter engaging with the pinions *j* aforesaid upon the lower ends of the distributors. The gears *S* and *U* are secured to the shafts *T*, turning in suitable bearings, *T'*, at the ends thereof, and the intermediate 45 gears, *V*, are fitted to turn in bearings formed in the stationary frames *R*.

It will be observed from the above description and Fig. 2 of the drawings that the rotary motion of the distributor is greatly increased 50 over that of the reel gear *H*, from which it is driven, said distributor being in practice turned about four or five hundred revolutions a minute. Therefore, as the rods are fed forward through the distributors and into the 55 reels in a red hot state they are laid in single continuous circular loops *g*, as aforesaid, out-

side of the central cones, *b*, the slow rotary motion of said reels causing said loops to be laid overlapping each other, as shown on the right-hand side of Fig. 1.

The distributors *Q*, (shown on the left-hand side of the drawings,) instead of being rotated, are swung forward and back by means of eccentrics *l* on shafts *T'*, which operate eccentric rods *m*, hinged at one end to the distributing pipes *n*, and provided at their opposite ends with straps *l'*, fitting over said eccentrics *l*. (See Fig. 1.) The upper ends of the pipes *n* are hinged to the inner ends of the stationary frames *R'*, and provided with trumpet-shaped openings similar to those of the distributors *Q*. The shafts *T'*, on which the eccentrics are secured, are fitted in bearings and operated similar to the shafts *T*, hereinbefore described.

The distributing-pipes *n* being moved forward and back, as above described, in connection with the slow rotary motion of the reels *D*, causes the rods as they are fed forward to be laid in oval loops *k* in said reels around the outside of the central cone, *b*, as shown on the left-hand side of Fig. 1.

The modification last described, as will be obviously seen, produces a similar result to that obtained by the use of a rotary distributor, and may therefore be employed without departing from the principle of my invention, or any other similar device used whereby the rods may be laid in single continuous loops of different shapes around the central cones, *b*, of the reels.

In practice I employ suitable switching devices for guiding the rods from the primary train into the conducting-pipes *o*, through which said rods are conducted to the several distributing devices, and thence to their respective reels *D*. Similar switching devices and conducting-pipes are also used for guiding and conducting the rods from the inclosed reels aforesaid to the supplementary trains, with which my improved reeling apparatus is 100 designed to be used, as hereinbefore stated.

By the employment of a group of reels, as hereinbefore described, it is obvious that a great saving in time is effected in the manufacture of wire rods, the operation of both filling and emptying the reels being carried on simultaneously; or, in other words, while a rod is being deposited in one reel, as hereinbefore described, (which is done in a very rapid manner, said rods being, in practice, fed forward at the rate of about thirty feet per second,) the rods on the filled reels may be drawn off onto storing reels for further treatment, or to the supplementary trains, in a much less rapid manner, thus admitting of said storing-reels or supplementary trains being run at a comparatively low rate of speed, and consequently economizing in the wear and tear of the same.

The use of a group of reels, as hereinbefore described, when used in combination with a primary and supplementary mills, enables the

reduction of rods by rolling to much smaller sizes than by the usual methods. They also lessen the cost of production, as well as the liability to injury of the employés.

5 In unwinding a rod from a filled reel its free end is first passed up through the central opening, *p*, in the cover *W*, then over the grooved wheel *q*, and from there to the storing-reel or supplementary mill, as the case 10 may be. The wheel *q* is mounted in a swivel-frame, *q'*, fitted to turn on the hub *r*, formed on the cover *W*, so as to admit of the rod being drawn in any direction from said reel. The cover *W* is also provided with an opening, *s*, through which to feed in the rods, and 15 is hinged to the top plate, *X*, of the machine at *t*, so that it may be swung around, as shown at *W'*, Fig. 1, to reach the inside of the reel, when required.

20 Having now fully described my said invention, and the manner of carrying the same into effect, what I claim, and desire to secure by Letters Patent, is—

1. In an apparatus for receiving wire rods 25 from a rolling-mill, the combination of the inclosed reel and the movable distributor for depositing the rod in continuous loops or coils within said reel and between its periphery and core, substantially as described.

30 2. The combination of the inclosed reel, the conducting-pipe, and the movable distributor for depositing the rod brought by said pipe within said reel, said distributor having a movement in a path between the periphery of the reel and its core, so that it deposits the 35 wire in continuous loops or coils outside of said core, substantially as described.

3. The combination of the reel, the means for rotating the same, the distributor for de-

positing the rod in said reel, and the means 40 for imparting to said distributor a movement between the periphery of the reel and its core, substantially as and for the purpose set forth.

4. The combination of the reel, the distributor consisting of a pipe or tube having its 45 discharge-orifice directly above said reel and between the periphery and core thereof, and shafts and connections, as described, for imparting a slow movement to said reel and a more rapid movement to said distributor, sub- 50 substantially as and for the purpose set forth.

5. The improved reeling mechanism described, comprising, in combination, an inclosed reeling-receptacle, a stationary cover having an opening therein to one side of the 55 center of said reel, a distributing-pipe supported above said opening, and shafts and connections, as specified, for imparting a rotary motion to said reel, and for moving said distributing-pipe so that it will deposit the rod 60 in successive coils or loops within said reel and between the periphery and core thereof, substantially as set forth.

6. The improved reeling mechanism described, comprising, in combination, the inclosed rotatory reel, the stationary cover therefor having an opening therein to one side of the center thereof, the conducting-pipe, the movable distributor above said opening, and the pulley for guiding the rod as it is drawn 70 out of said reel, substantially as set forth.

In testimony whereof I have signed this specification in the presence of two subscribing witnesses.
